RUNABOUT POWER BOAT

Richard C. Cole, 19701 Whispering Pines Road,
Miami, Fla. 33157

Filed Aug. 7, 1973, Ser. No. 386,299

Term of patent 14 years

Int. Cl. D12—06

U.S. Cl. D12—62

FIG. 1 is a side elevational view of a runabout power boat showing my new design.

FIGS. 2 and 3 are top and bottom plan views respectively, and

FIGS. 4 and 5 are rear and front elevational views respectively.

I claim:

The ornamental design for a runabout power boat, substantially as shown.
